UNITED STATES PATENT OFFICE.

ROY BOUGHNER, OF OTTAWA, ONTARIO, CANADA.

BOX CONSTRUCTION.

Application filed June 18, 1926. Serial No. 116,940.

My present invention appertains generally to improvements in the art of boxes, cartons and the like, and specifically to a container for rolled paper, such as waxed paper, 5 extensively used for household purposes, as described in the present specification and illustrated in the accompanying drawings.

Paper of this kind is usually sold to the customer in an oblong box provided with a 10 cover having a depending front ledge, so that when a portion of the paper is withdrawn from the box, it may be torn off evenly by a quick back and lateral motion, the edge of the ledge of the cover serving as a straight 15 edge against which the paper is torn.

Containers of this design, however, have many subversive features, among which I 20 may cite the awkward manner in which the same must be supported by the hand when the cover is opened to enable gripping of the free edge of the roll of paper, in order that it may be withdrawn; the difficulty of gripping the free edge of the paper when it has slipped back into the container and lies contiguous 25 with the roll, this being due to the depth of the front of the container; and the absence of constraining means to preclude the roll from rolling out of the box and unwinding when the box is upset or thrown down 30 carelessly.

Cognizant of the above, the primary object of my invention is to provide a container having a top and front which are relatively narrow compared with the width and depth 35 of the container, leaving a longitudinal opening for insertion and removal of a roll of paper, which lies in a diagonal plane with respect to the top of the container, and a cover for said opening shaped to substantially correspond with the other corner of 40 the box.

The advantages of such a construction are 45 that the box may be picked up in a natural way, with the thumb of the hand over a portion of the top thereof, and when the corner cover is elevated, the thumb need not be shifted, thus obviating the necessity of releasing the box to withdraw the free edge of the paper therefrom by the other hand.

A further advantage is that the front wall 50 of the box is comparatively narrow, so that one can get the fingers into the same easily to grip the free edge of the roll of paper.

Another advantage of the invention is that 55 there are four sides or walls to the container, so that when the same is upturned or thrown

down carelessly, the roll of paper will not roll out and become unwound.

Furthermore, by reducing the width of the portions or walls, the rigidity of the container is greatly increased.

Before tearing off a portion of the paper, by shifting the thumb slightly forward on the top of the corner cover, the same may be pressed down firmly and consequently by 65 having the hinged edge along the edge of the top about the middle of the container, and the narrow front, pressure exerted on the corner cover contacts the free edge thereof against the front of the container and retains the paper therebetween, thus preventing slipping of the paper and facilitating the tearing off operation.

For displaying purposes, the box is shallow, requiring less space on the counter, and 75 more clearly discloses the roll of paper therein, due to the location of the opening along the corner thereof.

Other objects and advantages will become apparent ensuing a perusal of the following 80 specification to read in conjunction with the annexed drawings, in which Fig. 1 is a transverse section of the container, showing the corner cover closed and a roll of paper therein.

Fig. 2 is a perspective view, showing a portion of the box, a roll of paper therein, the corner cover elevated and the position of the hands holding the container and removing the free edge of the roll of paper. 90

Fig. 3 is an end elevation of the container.

Like numerals of reference indicate corresponding parts in the different views.

The container includes a bottom 4, a back 5 of corresponding width, a relatively narrow top 6 and a front 7 of the same width as said top, leaving between the latter two components a longitudinal opening 8 extending from the end 9 to the end 10, and lying in a diagonal plane, with respect to said top 100 or bottom.

A corner cover, formed of two walls, indicated at 11 and 12, disposed at right angles, and ends 13 and 14, is hinged by means of a strip of cotton stay tape, which preferably extends longitudinally of the container and cover, to said top. The opposite edge of the cover is free to abut the front 7, when closed.

The opening 8 is made just wide enough 110 to admit the roll of paper A. The free edge B thereof extends between the front 7 and

the free edge of the wall 12 of the cover for tearing off purposes.

- The customary manner in which a box, or in fact any article of this nature is held when picked up, is that the thumb of the left hand extends over the top a piece and the fingers of the hand support the bottom of the same. I have constructed my container so that it may be picked up in a similar manner and when the cover is lifted to withdraw the free edge B of the roll of paper A from the same, it is not necessary to move the thumb or release one's grip on the container. This is clearly shown in Fig. 2, wherein I have indicated the left hand by the character C and the right hand by the character D. The thumb of the left hand C is bearing upon the top 6 and the fingers thereof support the bottom 4. The right hand D has lifted the corner cover and the free edge of the paper has been gripped and is being withdrawn for tearing off purposes. When this free edge B is withdrawn the required length, the thumb of the left hand is shifted over the corner cover to press the same down firmly. By having the hinged point for the corner cover in the position illustrated, pressure exerted by the thumb of the left hand will cause the free edge of the front 12 of the corner cover to press tightly against the upper edge of the front 7 at the point indicated at E. This holds the paper firmly and greatly facilitates the tearing off operation. It will also be appreciated that the relative shallow or narrow front 7 will permit one to extend the fingers around the front of the roll of paper A to grip the free edge B thereof in the event that it has slipped back over the roll from between the front 7 and free edge of the cover 12, with ease and without distorting the front 7 of the box as is necessary with containers, the front walls of which correspond in width with the backs. One of the disadvantages of other boxes for holding rolls of paper, is that pressure on the cover causes a buckling of the tearing

edge, so that an uneven edge is made on the paper torn. By the present construction, I overcome this undesirable feature by the formation of the box relative to the cover. At the angle between walls 11 and 12 of the cover, there is no longitudinal edge of the front 7 to contact with. In my construction the pressure, when the cover is held down, is at the ends where the ends 9 and 10 join the front 7. Thus the wall 12 is free to contact flat against the front 7. The pressure of the thumb on the cover, when paper is being torn, will not cause a buckle in the wall 12.

The four sides of the box also keeps the roll of paper A from rolling out and becoming unwound when the box is upturned or thrown down carelessly. This is an important feature of my invention.

Furthermore, by making the top 6 and front 7 relatively narrow in width, the rigidity or stiffness of same is greatly increased when compared with boxes or containers now in use, thus increasing the period of time for which the box may be used and preventing distortion or damaging of same in transit.

Minor changes in the form of construction may be resorted to in the commercial adaptation of my invention without departing from the spirit of my invention and scope of the annexed claim, but:

What I claim as new is:

In combination with a roll of paper, a container, including a bottom, a back and ends; a narrow top adjacent said back; a narrow front adjacent said bottom; a cover hinged from said top and overlapping said front when in normal closed position; the edge portion of said paper normally projecting between said front and the free edge of said cover; the free edge of said cover being adapted to act as a tear-off edge for said portion.

In testimony whereof, I affix my signature.

ROY BOUGHNER.
